UNITED STATES PATENT OFFICE.

HENRY RICHARDSON, OF CHICAGO, ILLINOIS.

WIRE FABRIC.

1,248,552.

Specification of Letters Patent.

Patented Dec. 4, 1917.

Application filed January 2, 1914. Serial No. 809,854.

To all whom it may concern:

Be it known that I, HENRY RICHARDSON, a subject of the King of Great Britain, residing at Chicago, in the county of Cook and 5 State of Illinois, have invented certain new and useful Improvements in Wire Fabrics, of which the following is a specification.

This invention relates to wire fabrics, and has reference more particularly to wire link 10 fabrics of the kind at present extensively used to form the bottoms of beds, couches, and like articles of furniture.

A type of bed and couch fabric at present extensively used is characterized structurally 15 by the presence of parallel longitudinal strands composed of interhooked bent wire units or links that are connected transversely at intervals by wire cross links. The interhooking of the ends of the links that form 20 the longitudinal strands in this type of fabric creates a weakness in the fabric at those points of connection, owing to the liability of the free or unsecured ends of the hooks to pull or straighten out under strain. 25 This same weakness also inheres in fabrics wherein the end portions of the wire forming each link are connected merely by interengaging hooks on said ends or by a hook on one end engaging a loop on the other, since 30 in all such cases there is present in the link at or intermediate its ends one or more hooks having a free or unsecured bent portion in the direct line of longitudinal strain, the strength of which to resist tensional strains 35 is far below the breaking point of the wire itself.

The general object of my present invention is to provide a new and improved wire link fabric structure of a type heretofore 40 originated by me and which is specially characterized by the fact that it employs two-ply links each formed from a single piece of wire in each longitudinal strand and may be made of a considerably lighter 45 gage of wire than was theretofore known in fabrics of that character. This object I accomplish by a novel structure of link that, in common with the type above referred to, entirely obviates the presence anywhere in a 50 fabric of the type described of unsecured ends of loops or hooks in a line or lines of strain.

My present invention relates to wire link

fabrics of the type employing separate cross links for connecting adjacent longitudinal 55 strands; and in the accompanying drawings I have illustrated my invention in several slightly varied forms, and referring there- to—

Figures 1, 3, 5, 7 and 10 are fragmentary 60 top plan views of wire fabrics embodying my invention in slightly varying forms as regards the structure of the main longitudi- 65 nal links. Figs 2, 4, 6, 8 and 11 are enlarged fragmentary views in bottom perspective of 70 portions of the main longitudinal links shown in Figs 1, 3, 5, 7 and 10, respectively, and more particularly illustrate the disposi- 75 tion of the extreme terminal portions of the wire forming each link. Fig. 9 is a detail 80 view in top perspective of a portion of the fabric illustrated in Figs. 7 and 8.

The novel fabric of my invention, in all 85 of the forms illustrated, includes a plurality of links or units each composed of a single 90 length of wire bent upon itself to provide the characteristic features, common to all of the forms shown, of a two-ply body member having closed ends, with the terminal portions of the wire tied together or otherwise 95 interlocking engaged with each other and having their free ends clenched to the body member, and a plurality of cross links that are flexibly connected at their ends to and between adjacent longitudinal strands.

In all the embodiments of the invention herein presented, the wire of which each main longitudinal link is composed is bent in such a manner as to provide a two-ply 100 body or tension member 10 the limbs of 90 which are joined at one end preferably by means of a simple U-bend or loop 11, and are joined at the other end by means of a two-ply loop 12 (Fig. 9) the sides of which two-ply loop are integrally joined across the 95 body member. Furthermore, in all of the forms illustrated the end portions of the wire are tied together by crossing each other in an interlocking manner between the ends of the links and in the line of one limb of 100 the body member, and are thence extended across and clenched to the body member. Figs. 1 and 2 illustrate the simplest form in which this may be done, wherein 13 and 14 designate rectangular extensions of the two 105 portions of one limb of the body member

interlockingly crossing each other at their junctions with the body member; the member 13 extending across one side of one limb of the body member and having its extreme 5 terminal portion 15 clenched to the body member, and the member 14 extending in the opposite direction across both limbs of the body member and having its extreme terminal portion 16 also clenched to the latter, as most clearly shown in Fig. 2.

In the form of the invention shown in Figs. 3 and 4, the extension 14, 16, is formed the same as in Figs. 1 and 2. The other end portion of the wire is, however, curled 15 around the member 14 at its junction with the body member, as shown at 17, is thence extended across both limbs of the body member below the member 14, as shown at 18, and its extreme terminal portion 19 is clenched to 20 the body member alongside of and extending in the same direction as the terminal portion 16, as clearly shown in Fig. 4.

In the form of the invention illustrated in Figs. 5 and 6, the end portions of the 25 wire are so bent as to form interengaging eyes 20 and 21, whence the wires extend in the same direction across one side of the body member, as shown at 22 and 23, and their extreme terminal portions are clenched 30 to the body member as shown at 24 and 25 in Fig. 6.

In the form of the invention illustrated in Figs. 7, 8 and 9, the end portions of the 35 wire are tied together and clenched in the same manner as shown in Figs. 3 and 4, but the adjacent end portion of the body member, beyond said junction of the wire ends, is given a half-twist, causing the two limbs of the body member to cross each other as 40 shown at 26.

In the form of the invention illustrated in Figs. 10 and 11, the two limbs of the body member adjacent to the closed end 11 are given a complete twist (that is, are twisted 45 through three hundred and sixty degrees), as shown at 27, and the interlocking portions 28 and 29 of the wire below said twist extend across the body member in opposite directions, the portion 29 being curled 50 around the portion 28 in the same manner as in the forms shown in Figs. 3 and 7, and the extreme ends 30 and 31 are clenched to the body member, as shown in Fig. 11.

In all forms of the invention, the longitudinal strands of the fabric are flexibly 55 connected by means of cross links 32. On the ends of these cross links 32 are formed closed loops 33 that preferably interloop with the longitudinal links just inwardly 60 of the U-bends of the latter, and the free ends of the loops 33 are secured against pulling out under strain by being extended across and clenched to the body portions of the limbs as shown at 34. By reason of

this formation of the cross-links greatly 65 increased tensional strength is afforded to the fabric in a transverse or crosswise direction.

The preferred manner in which the longitudinal links or units are connected end to 70 end in the fabric is clearly apparent from the drawings; the terminal bends or loops 11 and 12 of endwise adjacent links being simply interlooped or carried through each other, in the manner most plainly indicated 75 in the perspective view Fig. 9.

The described disposition of the free ends of the wire beyond the interlock has the effect not only of greatly increasing the tensional strength of the fabric, but also of 80 tying together the two limbs of the body member of each link, thus preventing lateral spreading of said limbs under cross strains.

The crossing or twisting of the twin limbs of the body member near one end of the 85 latter as suggested in Figs. 7 to 11 inclusive, is not essential to the carrying out of the invention, but is useful in the case of very light wire, since it to a certain extent reduces the degree of strain to which the 90 clenched terminal portions of the wire are subjected.

I claim—

1. A wire link fabric, including a plurality of longitudinal links each consisting of 95 a single length of wire bent to provide a two-ply body member and having the end portions of said wire interlockingly engaged with each other at a point intermediate the ends of said body member, thence extending 100 crosswise of said body member, and at their extreme ends clenched beneath the latter, said longitudinal links being flexibly connected end to end to form the longitudinal strands of the fabric, and cross links flexibly 105 connecting adjacent longitudinal strands.

2. A wire link fabric, including a plurality of longitudinal links each consisting of a single length of wire bent to provide a two-ply body member and having the end 110 portions of said wire interlockingly engaged with each other at a point intermediate the ends of said body member and thence extending in opposite directions crosswise of and anchored to said body member, said longitudinal links being connected end to end to form the longitudinal strands of the fabric, and cross-links flexibly connecting adjacent longitudinal strands.

3. As an article of manufacture, a wire 120 fabric link consisting of a single length of wire bent to provide a two-ply body member, and having the end portions of said wire interlockingly engaged with each other at a point intermediate the ends of said 125 body member, and thence extending in opposite directions crosswise of and anchored to said body member.

4. As an article of manufacture, a wire fabric link consisting of a single length of wire bent to provide a two-ply body member, and having the end portions of said wire interlockingly engaged with each other at a point intermediate the ends of said body member, thence extended crosswise of

said body member, and at their extreme ends secured beneath the latter.

HENRY RICHARDSON.
